CHAIR

Ralph M. Galloway, 601 S. Audubon Ave., Tampa, Fla.

Filed Feb. 25, 1960, Ser. No. 59,523

Term of patent 14 years

(Cl. D15—1)

FIG. 1 is a front elevational view of a chair showing my design; and

FIG. 2 is a side elevational view thereof.

The top of the seat cushion is conventional while the back of the chair is formed of plywood and is unornamented except for the exposed graining of the wood, both front and back.

I claim:

The ornamental design for a chair, as shown and described.
